UNITED STATES PATENT OFFICE.

COLIN KENDRICK, JR., OF NEVADA CITY, CALIFORNIA.

VALVE-GEAR FOR ORE-STAMPS.

SPECIFICATION forming part of Letters Patent No. 451,765, dated May 5, 1891.

Application filed January 23, 1891. Serial No. 378,739. (No model.)

To all whom it may concern:

Be it known that I, COLIN KENDRICK, Jr., of Nevada City, in the county of Nevada and State of California, have invented certain new and useful Improvements in Valve-Gears for Ore-Stampers; and I do hereby declare that the following is a full, clear, and exact description thereof, reference being had to the accompanying drawings, and to the letters of reference marked thereon, which form part of this specification, in which—

Figure 1 is a perspective view of my improved valve-gear for twin-cylinder engines. Fig. 2 is a plan view. Fig. 3 is a detail view.

15 This invention is an improvement in valve-operating gear for twin-cylinder engines; and its object is to make one engine assist in operating the valves of the other and to so connect the valve-rods of the two engines that 20 they will be operated simultaneously but oppositely, and to enable the time of operation of the valves to be regulated, so that the steam, &c., can be cut off at various points in the stroke of the piston, so that the strokes of 25 the pistons may be cushioned more or less, and, further, to operate the valves suddenly and quickly, instead of gradually, all of which will be accomplished by the means hereinafter clearly set forth and claimed.

30 Referring to the drawings by letters, K K designate twin cylinders of ordinary construction; I I, the piston-rods, which, as indicated, project through both ends of the cylinder, (the drawings representing cylinders of a 35 vertical engine or stamp-mill,) and J J are slide-valve chests, and H H the valve-rods. The valves are of any suitable construction.

j designates a bracket-casting attached to the chests and having its central portion rising 40 above the tops of the chests, and G is a vertically-oscillating bar centrally pivoted on bracket j, as indicated. The ends of bar G are connected to pieces M M, pivotally connected by one end to the upper ends of rods H, preferably in such manner that the pieces may have 45 a horizontal but no vertical play in relation to the ends of the bar. The upper ends of pieces M are connected by a universal joint D with the lower ends of straps L L, the upper ends of which are pivotally connected to levers A A about centrally thereof, and these levers are in turn each pivoted at one end to

the end of an arm C, attached to the valve-chest or other suitable support. Levers A A thus overlie the valve-chests and cylinders, 55 as indicated, and in the free end of each lever is an adjustable impact-bolt F, which will be struck by the projecting end of the piston-rod when the levers are lowered.

Owing to the connections between bar G, 60 valve-rods H, and lever A A, when one lever and valve-rod are depressed the other lever and valve-rod are elevated, so when steam is admitted into the lower end of one cylinder it will be admitted into the upper end of the 65 other, and vice versa. In operation steam is admitted into the cylinders so as to move the pistons in opposite directions. The ascending piston-rod as it nears the end of its stroke suddenly strikes the bolt F of the overreaching lever A and moves the same upward. This movement of the lever, through its connection, lifts its connected valve-rod H and adjoining end of bar G, while the opposite end of the bar, being thereby depressed, 75 causes the opposite valve-rod and its connected lever to move downward. The levers A are thus operated alternately by the piston-rods as they ascend during the operation of the machine. As the levers A are not 80 moved until the piston-rods are near the ends of their stroke, the valves are shifted quickly and suddenly, and by adjusting impact-bolts F the amount of oscillation of levers A and the moment of impact of the pitman-rods 85 can be varied, as is evident. The invention can be worked with ordinary engines, wherein the piston-rods do not extend through both ends of the cylinder, simply by attaching striking-blocks to the rods, as is obvious, the 90 levers A standing in front of the cylinders instead of in rear thereof.

Having described my invention, what I claim as new, and desire to secure by Letters Patent thereon, is—

95 1. The combination of the cylinders, the piston-rods, valve-chests and valve-rods, and the oscillating bar connected to said valve-rods, with the opposite levers pivoted to fixed supports at one end and adapted to be struck 100 and shifted by the pitman-rods alternately, and the connections between said levers and valve-rods, substantially as and for the purpose described.

2. The combination of the cylinders, valve-chests, piston and valve rods, an oscillating bar connected at its ends to the valve-rods, the levers pivoted at one end to fixed supports, the link connections between said levers and valve-rods, and the impact-bolts in the free ends thereof adapted to be contacted by the piston-rods, substantially as set forth.

3. The combination of the cylinders, valve-chests, piston and valve rods, the levers pivoted at one end to suitable supports, the straps connecting said levers to the valve-rods, and the adjustable impact-pieces on the

free end of said levers, with the oscillating bar fulcrumed on a support between the valve-rods and having a loose connection at its ends to the valve-rods, all constructed and arranged to operate substantially as and for the purpose specified. 15

In testimony that I claim the foregoing as my own I affix my signature in presence of two witnesses.

COLIN KENDRICK, JR.
